Charles J. Hunt.

UNITED STATES PATENT OFFICE.

ARTHUR W. TUTTON, OF EAU CLAIRE, MICHIGAN.

HAY-CARRIER.

SPECIFICATION forming part of Letters Patent No. 380,412, dated April 3, 1883.

Application filed August 22, 1887. Serial No. 247,578. (No model.)

To all whom it may concern:

Be it known that I, ARTHUR W. TUTTON, of Eau Claire, in the county of Berrien and State of Michigan, have invented a new and useful Improvement in Hay-Carriers; and I hereby declare that the following is a full, clear, and exact description thereof, reference being had to the accompanying drawings, which form a part of this specification.

10 My invention relates to an improvement in hay-carrying apparatus of that class in which the carrier runs on a cord or line or other suspended track; and the invention consists in bifurcating and slotting the shank or latch 15 of the catch, passing the lever of the supporting-hook through the slot of the catch-lever, and in the means for arresting and retaining the carrier and releasing the supporting hook or catch.

20 Figure 1 is a view of the carrier with the side removed. Fig. 2 is a view of the latch of the retaining-catch detached. Fig. 3 is a view of the supporting-catch detached. Fig. 4 is a view of the stop on the line.

25 A is the body of the carrier, supported on the cord B by the grooved wheels C C, which are pivoted in the upper section of the carrier by the pivots c c.

The hay-carrier is described as running on 30 the cord B; but it may be run on any other track as well, as this feature is not claimed as a part of my invention.

In the lower section of the carrier is pivoted the pulley D by means of the pivot d, to 35 which is also pivoted the bifurcated end e e of the latch E, which is also slotted at e', and at its free end terminates in the catch F with the beveled point f.

H is a lever pivoted in the carrier on the 40 pivot J, and passes through the slot e' in the lever E, and terminates at its lower end in a hook or catch, I, which engages with the loop k on the pulley-block K, to which the hay-fork is attached, and supports the load to 45 be conveyed by the carrier. The upper arm, h, of the lever H extends above the pivot J far enough to allow the bar g of the stop G to engage with it and force it back so as to release the catch I from the loop k of the pul-

ley-block K. The spring O is connected at 50 one end with the arm h of the lever H, and at the other end to the latch E, and returns the lever H to its position when released from the pressure of the bar g of the stop G. The bar g of the stop G is grooved upon its upper surface to receive the cord B, to the under side of which it is fastened in any convenient manner. To the bar g is riveted the two wings g' g', which project downward and flare outwardly. These wings are united at their 55 front ends by the bar or rod L, which, in operation, engages with the catch F of latch E, and retains the carrier in place until the fork is loaded. At the same time the front end of the bar g presses back the top of the lever H, 60 and the hook or catch I is disengaged from the loop of the pulley-block, and the fork falls into the hay on the wagon which is to be unloaded. To the post or rod M is attached the line N, which is run through the pulley-block K and passes up over the pulley D, and is carried out to any convenient point.

When the carrier is over the wagon and the fork loaded, the free end of the line N is drawn down, and the pulley-block K is raised 75 until the loop k passes above the catch I of lever H, and, striking against the latch E, disengages its catch F from the bar L of the stop, and as the carrier moves back the upper end of the lever H is freed from the pressure of the bar g of the stop, and its catch I engages in the link k and supports the pulley-block K with the hay-fork during the forward movement of the carrier. When the carrier arrives at the proper point, the fork is 80 tripped in the usual manner and the hay deposited in the mow. The carrier is then returned for another forkful, and this process is repeated until the wagon is unloaded and the hay stowed away in the mow. 90

It will readily be seen that in my invention the construction of the hay-carrier is greatly simplified and its operation facilitated.

What I claim as my invention is—

1. In a hay-carrying apparatus, the combination of the bifurcated slotted latch E with the lever H and spring O, substantially as and for the purposes described. 95

2. In a hay-carrying apparatus, the combination of the bifurcated slotted latch E, lever H, spring O, and the stop G on the cord B, substantially as described.
- 5 3. In a hay-carrying apparatus, the combination of the bifurcated and slotted latch E, lever H, spring O, stop G, pulley-block K,

provided with the loop k, the line or cord N, and the pulley D, substantially as and for the purposes specified.

ARTHUR W. TUTTON.
